ROLLIN ABELL, OF MILTON, MASSACHUSETTS, ASSIGNOR TO J. B. CARBURETOR CORPORATION, OF LOS ANGELES, CALIFORNIA, A CORPORATION OF CALIFORNIA.

CARBURETER.

1,265,024.

Specification of Letters Patent.

Patented May 7, 1918.

Original application filed November 9, 1911, Serial No. 659,393. Divided and this application filed October 14, 1915. Serial No. 55,801.

To all whom it may concern:

Be it known that I, ROLLIN ABELL, a citizen of the United States, and resident of Milton, in the county of Norfolk and State 5 of Massachusetts, have invented certain new and useful Improvements in Carbureters, of which the following is a specification.

This invention relates to carbureters, and the present application is a division of my 10 application Serial No. 659,393, filed November 9, 1911, which resulted in Letters Patent No. 1,158,359, dated October 26, 1915.

The carbureter, in so far as the present application is concerned, embodies a structure whereby the starting of an internal combustion engine is facilitated and whereby the continued carbureting operation is facilitated. For the purpose of facilitating starting, the carbureter is constructed to 20 seal the primary air conduit with gasoline or whatever liquid hydrocarbon fuel is used, the bulk of sealing liquid being so small that it is readily carried off by the air which passes through the primary air conduit, and, when so carried off, the seal is 25 disrupted and cannot form again so long as the flow of air through the primary air conduit is continued. The seal, however, forms automatically whenever the flow of 30 air through the primary air conduit ceases, and consequently there will always be in the primary air conduit, when starting, a sufficient quantity of liquid fuel to "wet" the walls of the mixing chamber and to insure 35 a combustible mixture, regardless of weather conditions.

After the sealing liquid has been carried off as hereinbefore explained, the liquid fuel flows by gravity into the primary air conduit, and the carbureting operation is therefore effected more easily than would be the case if air tension were required to lift the liquid to the point where it could be atomized.

45 While the carbureter is in operation the discharge of liquid fuel into the primary air conduit is controlled by a valve. At the same time, a secondary supply of air is admitted into the mixing chamber under the 50 control of a gravity-closed valve which is free to rise and fall as the air tension set up by the engine increases or diminishes. The volume of the secondary supply of air will be the difference between the capacity

of the primary air conduit and the volume 55 required by the engine, the air tension in the primary air conduit being thus maintained substantially constant. In order to control the feeding of liquid fuel in accordance with the speed of the engine, the liquid-controlling valve is connected to the secondary air valve so that the up and down movements of the latter will be transmitted to the liquid-controlling valve. The two valves are thus caused to open and close in 60 unison, and by them the proportions of air and liquid fuel are maintained substantially constant at all speeds of the engine. The aforesaid connection between the two valves is capable of adjustment for the purpose of 65 varying the proportion of liquid fuel relatively to the air.

70 Of the accompanying drawings, which illustrate one form in which the present invention may be embodied:

75 Figure 1 represents a vertical section through a carbureter whose parts are in normal position, as when the device is not operating.

Fig. 2 represents a horizontal cross section in the plane indicated by line 2—2 of Fig. 1.

The same reference characters indicate the same parts wherever they occur.

The carbureter comprises a casing 10 85 which provides a fuel chamber 11, and a casing 12 which provides a mixing chamber 13. I have shown means for automatically feeding liquid fuel such as gasoline into the chamber 11 to a predetermined level, and 90 the supply pipe therefor will be coupled to a nipple 14. The delivery of fuel into the chamber 11 will be controlled by a valve 15, float lever 16 and float 17. The level of liquid fuel maintained by the float will be 95 at or near line x.

The casing 10 is covered by a plate 18, and the casing 12 is affixed to said plate by screws 19. Lugs 20 are formed on the bottom of the casing 12 to provide a sufficient 100 space 21 between the two casings to admit the air supply. The primary air supply flows downwardly from the space 21 into a well 22 and thence upwardly through a tubular member 23 whose upper end is arranged in the mixing chamber 13. The well 22 is formed in a sleeve 24, the latter being formed, in the present instance, as an inte-

gral part of the plate 18. The tube 23 is in the form of an elongated pinion, having teeth 25 for a purpose hereinafter explained. The spaces between the teeth 25 provide the 5 necessary passageways for the primary air to flow from the space 21 into the well.

The secondary air flows directly from the space 21 into the mixing chamber 13 through an opening 26 in the bottom of said chamber. 10 This opening is normally closed or substantially closed by a secondary air valve 27. The wall 28 is tapered so as to admit an increasing volume of secondary air as the valve 27 rises. A post 29 is affixed to the cover 15 plate 18 and extends through the valve 27. This post has a bottom shoulder 30 upon which the valve rests when in its lowest position. The upward movement of the valve is limited by a collar 31 on the post, said collar 20 in the present instance being in the form of a nut and being screwed upon the post. The chief function of the post is to prevent rotation of the valve 27, for a purpose hereinafter described.

25 The fuel flows from the chamber 11 through a duct 32 in the member 24 to a vertical duct 33. Duct 33 extends through a delivery nozzle 34 whose upper end is a sufficient distance below the normal level α 30 of liquid, to enable the liquid to overflow into the well 22. Consequently, when the device is not operating, the liquid fuel will fill the well 22 as well as the chamber 11 up to the level α . Inasmuch as the tube 23 extends a substantial distance below the level 35 of the liquid, the primary air conduit will be normally sealed by liquid fuel. When the device is operating, the discharge of liquid from the nozzle 34 is controlled by a valve 40 35. This valve is connected to the secondary air valve 27 so as to be opened and closed automatically as the latter opens and closes. For this purpose the tube 23 is connected to the valve 27 by screw-threads 36, said tube 45 being thus caused to rise and fall with the secondary air valve. The fuel valve 35 is carried by a pin 37 which in turn is carried by the tube. The pin-receiving hole 38 of the fuel valve is enough larger than the pin 50 to enable the valve to be centered by the nozzle 34 and to move freely up and down in the nozzle without binding therein.

The screw-threaded connection between the tube 23 and valve 27 is provided for the 55 purpose of adjusting the fuel valve relatively to the valve 27. I have shown a spur gear 39 arranged to mesh with the teeth 25 of the tube. Gear 39 is mounted upon a stud 40 set in the plate 18. When the gear is 60 rotated it will screw the tube up or down relatively to the valve 27, according to the direction of rotation, and the relation of the two valves will be thus varied. It may be explained at this time that the chief function 65 of the post 29 is to hold the valve 27

against rotation so that the desired adjustment of the fuel valve will be insured when the tube is rotated. It may also be explained that the teeth 25 of the tube may slide up and down freely between the teeth of the 70 gear 39.

I have shown a thermo-responsive element 41 arranged to act upon the gear 39 to adjust the valve 35 automatically according to the temperature of said element. The element 75 41 may be made of laminae of different materials such as steel and brass which have unequal expanding and contracting actions. The element 41 as shown is in the form of a coil, the inner end thereof being anchored 80 to the stud 40 in a slot 42 formed therein. The outer end of the element 41 has a tongue 43 which is arranged in one of a series of holes 44 formed in the gear 39. The inner end of the element 41 being held stationary, 85 the outer end of said element will turn the gear 39 in one direction to raise the valve 35 as the temperature falls, or in the opposite direction to lower said valve as the temperature rises. The tongue 43 may be taken out 90 of the hole which it occupies and the gear 39 may be turned to bring another one of said holes into tongue-receiving position, this adjustment as between the element 41 and gear 39 affording the desired initial adjustment of the valve 35 relatively to the valve 27 and being the only manual adjustment required.

In order to explain the operation of the carburetor it will be assumed that the carburetor is attached to a manifold or other pipe (not shown) of an internal combustion engine, and that the combustible mixture will flow into said manifold or pipe through the outlet 45. Assuming that the engine is 105 at rest, it is evident that liquid fuel will fill the chamber 11, well 22 and tube 23, up to the normal level, which is a substantial distance above the top of the nozzle 34. The primary air conduit is thus sealed by the 110 liquid fuel, and the secondary air conduit or opening 26 will be normally or initially closed or substantially closed by the valve 27. I have said "substantially closed" because although the secondary air valve 27 115 would preferably completely close the opening 26 there might be a slight leakage when the valve is in its lowest position. However, for practical purposes it is sufficient if the secondary air opening is closed to such extent that upon starting the engine the suction caused by the first intake stroke of the engine will draw a substantial volume of air through the primary air conduit. The first intake stroke will therefore cause the 120 air to flow through the primary air conduit with sufficient velocity to disrupt the seal and carry the sealing fuel upwardly through the tube 23 and into the mixing chamber 13. It is thus assured that the first charge which 125

goes to the engine will be enriched sufficiently to insure prompt combustion. As the speed of the engine increases, the force of the intake suction increases accordingly, and when 5 the combined weight of the valve 27, tube 23 and valve 35 is insufficient to sustain the tension they will be drawn upwardly to admit the secondary supply of air and an increasing volume of liquid fuel. The secondary 10 air opening grows larger as the valve 27 rises, and consequently the valve is always balanced with relation to the air tension on the one hand and the weight of the valves 27 and 35 and tube 23 on the other hand. The 15 valve 35 is tapered so that it will increase the discharge of liquid fuel from the nozzle substantially in proportion to the increase of the air supply.

Inasmuch as the tapering wall 28 takes 20 care of variations in the demand for air, the tension and velocity of air in the tube 23 will be constant. This constant velocity, as determined by the weight of the two valves 27 and 35, and the tube 23, is sufficient to 25 carry off the liquid as fast as the latter is discharged from the nozzle, so that it is impossible for the liquid to accumulate in the primary air conduit while there is vacuum tension in the mixing chamber. As 30 soon, however, as the engine stops, the two valves and the tube 23 drop to the position shown, the fuel valve 35 almost but not completely closing the outlet of the nozzle. Liquid fuel will therefore continue to overflow 35 the nozzle until it has risen in the tube and in the well 22 to its normal level above the top of the nozzle. The primary air conduit is thus automatically sealed again to insure prompt combustion when the engine 40 is next started.

I claim:

1. A carbureter comprising a well for liquid fuel, a nozzle extending upwardly in 45 said well, said well having an opening above the top of said nozzle to admit air, a suction tube arranged to carry air and liquid fuel from said well, the lower end of said tube surrounding said nozzle below the top of the latter, and means arranged to feed 50 liquid fuel through said nozzle to a predetermined level above the top of said nozzle, said well and suction tube coöperating to 55 form an air passageway to conduct air downwardly from said opening to a plane below said predetermined level and below the top of said nozzle.

2. A carbureter comprising a substantially vertical air suction tube arranged to suck air upwardly, a liquid fuel nozzle, the delivery end of which is arranged within said tube and arranged to discharge upwardly, and means arranged to feed liquid fuel through said nozzle to a predetermined level above the top of said nozzle, said tube 60 and nozzle being proportioned to restrict the

air passageway and liquid outlet so that the air sucked through said tube will have sufficient velocity to atomize and carry off the liquid which issues from said nozzle, and means arranged to prevent overflow of liquid 70 from the carbureter when the latter is not operating.

3. In a carbureter, a mixing chamber, a fuel chamber; an air chamber for both main and auxiliary air projecting downward into 75 the fuel chamber, an inspirator nozzle mounted within the projecting part, a suction valve, a fuel valve adapted to coöperate with said inspirator nozzle and means for normally adjusting it to cause fuel to creep 80 over the tip of said nozzle into the bottom of the air chamber and means to force the air through or over the puddle on its way to the mixing chamber, for the purpose described.

4. In a carbureter, a mixing chamber, an air chamber for both main and auxiliary air and a fuel chamber, mounted in a line one above the other, a suction valve between the mixing and air chambers, a fuel valve 90 carried thereby, a fuel puddle chamber integral with the air chamber and extending downward into the fuel chamber, an inspirator nozzle mounted in the air chamber and adapted to coöperate with the fuel valve 95 which is normally so adjusted with respect to the nozzle as to allow the fuel to creep over into the puddle chamber, for the purpose described.

5. A carbureter comprising a mixing 100 chamber having an air inlet at the bottom and a frusto-conical internal surface tapering toward said inlet, a gravity-operated air-valve arranged in said chamber to coact with said surface to regulate the inflow of 105 air through said inlet, a well arranged beneath said inlet, the top of said well being open to the atmosphere to admit air, a tubular valve-stem carried by said air-valve and projecting into said well to guide the valve 110 and to conduct fuel from said well into said mixing chamber, said well and said valve-stem providing a passageway for conducting air downwardly externally of the valve-stem, a stationary inspirator nozzle projecting upwardly into said valve-stem, means arranged to feed liquid fuel through said nozzle to a level above the mouth of the latter, and a tapered needle-valve arranged 115 within and carried by said valve-stem to move up or down in said nozzle as said air-valve moves up or down.

6. A carbureter comprising a mixing chamber having an air inlet at the bottom and a frusto-conical internal surface tapering toward said inlet, a gravity-operated air-valve arranged in said chamber to coact with said surface to regulate the inflow of 125 air through said inlet, a chamber for liquid fuel arranged beneath said inlet, a station- 130

ary nozzle projecting upwardly in the latter chamber, means arranged to feed liquid fuel through said nozzle, a tubular valve-stem carried by said valve and projecting downwardly therefrom to conduct fuel from the latter chamber to said mixing chamber, the lower portion of said valve-stem surrounding said nozzle, a tapered needle-valve arranged within and carried by said valve-
10 stem to move up and down in said nozzle, said air-valve and said valve-stem having connecting screw-threads to permit adjustment of the latter relatively to said air-valve, said valve-stem having external teeth, and a gear arranged to coact with said teeth to adjust the needle-valve relatively to said air-valve.

7. In a carbureter, a mixing chamber, an air chamber for both primary and auxiliary air, a fuel chamber, a valve responsive to suction in the mixing chamber and a fuel valve controlled by the first mentioned valve, an inspirator mounted within said air chamber and opening at the bottom into the fuel chamber and having an opening at the top adapted to coöperate with the fuel valve to regulate the amount of fuel passing therethrough, said fuel valve having a self-aligning point, for the purpose described.

8. In a carbureter, a mixing chamber, a main air chamber, a fuel chamber, said main air chamber being supported on said fuel chamber and having a central annular air funnel projecting downward into the fuel chamber, an inspirator mounted within said air funnel and having an opening into the fuel chamber, a suction valve between said mixing and air chambers, a fuel valve adapted to co-act with said inspirator and controlled by said suction valve to regulate the flow of fuel through the inspirator.

9. In a carbureter, a mixing chamber, a

main air chamber and fuel chamber, said air chamber having an air funnel extending downward into the fuel chamber, an inspirator mounted within said air funnel, a circular port opening between the mixing and air chambers, a hollow suction valve, seated in said port and extending downward into the air funnel of said air chamber and encompassing said inspirator, and a fuel valve carried by said suction valve to regulate the flow of fuel through said inspirator.

10. In a carbureter, a mixing chamber, a main air chamber and a fuel chamber said air chamber having an air funnel extending downward into the fuel chamber, an inspirator mounted within said air funnel, a circular port opening between the mixing and air chambers, a hollow suction valve seated in said port and extending downward nearly to the bottom of the air funnel of said air chamber and surrounding the inspirator whereby air is drawn downward outside said valve and upward inside by the top of said inspirator, and a fuel valve supported within the hollow part of said suction valve and controlled thereby for regulating the fuel through said inspirator.

11. In a carbureter, a mixing chamber, a fuel chamber, an air chamber having an air funnel extending below the level of the fuel in the fuel chamber, an inspirator located in the air funnel and having an opening therein connecting with the fuel chamber, an opening between the mixing and air chambers, a suction valve seated in said opening, a fuel valve to coact with said inspirator and controlled by said suction valve.

In testimony whereof I have affixed my signature.

ROLLIN ABELL.
